DESIGN FOR A GAME BOARD

Herschel R. Hoskins and Frances M. Small,
Los Angeles, Calif.

Application November 29, 1946, Serial No. 135,184

Term of patent 3½ years

(Cl. D34—5)

To all whom it may concern:

Be it known that we, Herschel R. Hoskins and Frances M. Small, citizens of the United States, residing at Los Angeles, in the county of Los Angeles and State of California, have invented a new, original, and ornamental Design for Game Board, of which the following is a specification, reference being had to the accompanying drawing, forming part thereof.

The drawing illustrates a game board embodying our new design in which:

Fig. 1 is a plan view of the game board; and
Fig. 2 is a perspective view of the game board in partly closed position.

We claim:

The ornamental design for a game board, as shown.

HERSCHEL R. HOSKINS,
FRANCES M. SMALL.
